METHOD AND APPARATUS FOR CLASSIFYING MATERIALS.

1,392,401.

Specification of Letters Patent.

Patented Oct. 4, 1921.

Application filed July 8, 1918. Serial No. 243,911.

To all whom it may concern:

Be it known that we, HENRY M. CHANCE and THOMAS M. CHANCE, citizens of the United States, residing at Philadelphia, in 5 the city and county of Philadelphia, State of Pennsylvania, and at Baltimore, State of Maryland, respectively, have invented a certain new and useful Method and Apparatus for Classifying Materials, whereof the 10 following is a specification.

Our invention consists of an improved method and apparatus for classifying materials having different falling velocities in liquid, and may be carried out by the aid 15 of appliances similar to those in common use for the classification of ores, etc., such as are known as classifiers, jigs, surface current classifiers, trough washers, upward current classifiers, etc., and which are used in separating 20 rating, by means of differences in falling velocities in liquid, the materials to be treated into classes having equal, or approximately equal, falling velocities. If such appliances be used in separating materials of 25 different specific gravities, but of the same size, shape and character of fracture, the materials composing each class so separated will consist of particles having approximately the same specific gravity, but when 30 the individual particles of such materials differ materially in size or in shape, the slower falling classes so separated will contain relatively large pieces of light material, smaller pieces of heavier material and 35 flat or oblong pieces of both lighter and heavier material, while the more rapidly falling classes will contain relatively large pieces of heavy material with more or less of the flat or oblong pieces of the lighter 40 materials.

The object of our invention is to improve separations of this description by the use of fluid masses of higher specific gravity than the liquid constituent of such fluid 45 mass, whereby the differences in the relative weights of materials immersed in said fluid mass are greater than the differences in the relative weights of said materials when immersed in water or other lighter liquid.

Classification, or the separation of materials into classes of equal falling velocities, 50 actually depends not upon differences in the falling velocities of materials but upon differences in the retardation in the falling 55 velocities of materials of different specific

gravities, sizes and shapes. All materials in a vacuum fall with equal velocity, irrespective of weight, shape or size, but in falling through air, water or any fluid medium, the lighter, the smaller and the flat pieces 60 lying horizontally are retarded more than the heavier, the larger and the flat pieces lying vertically.

This retardation is greater in liquids of high specific gravity than in those of low 65 specific gravity, and is greater in viscous liquids than in liquids of high mobility or fluidity. The differences in retardation caused by the specific gravity of the liquid are due to the differences in the loss of 70 weight of materials immersed in the liquid, because in materials of relatively low specific gravity the losses in weight due to immersion may be a large percentage of their actual weights, while in those of relatively 75 high specific gravity the losses in weights due to immersion may be a small percentage of their actual weights. The differences in retardation caused by the viscosity of a 80 liquid in which the falling materials are immersed are in addition to those caused by the losses in weight due to the specific gravity of the liquid, and are due to the resistance to movement produced by the viscosity 85 of the liquid.

Retardation due to viscosity does not affect the falling velocities of materials of different specific gravities or of different sizes, or of different shapes in the same way that weight, size and shape affect falling 90 velocities in liquids of high mobility or fluidity, because the retardation of each particle due to viscosity depends upon the ability of each particle, by reason of its weight, not only to tear itself free from the viscous 95 envelop of liquid that is clinging to it, but to force apart the viscous liquid below it, making a path through which it can sink. The relatively small particles, those with 100 small masses and correspondingly small gravitational forces due to their small immersed weights, have relatively large surfaces (as compared with the masses and surfaces of larger particles) to which the viscous liquid adheres, and are retarded, relatively, more than the larger particles. On the other hand with particles of the same size, but of different specific gravities, the additional retardation caused by the viscosity 105 of the liquid, because of the differ- 110

- ence in the immersed weights of the particles, will be greater for those of low specific gravity than for those of greater specific gravity.
- 5 While this property of viscous liquids to retard (or to prevent) the sinking of small particles of relatively heavy material and larger particles of relatively lighter materials, may perhaps have useful application
- 10 in the arts, it becomes detrimental in the carrying out of our improved method for classifying materials by means of a fluid mass consisting of an agitated mixture of liquid and comminuted insoluble solid matter,
- 15 heavier than the liquid, this fluid mass being the medium in which and by which classification is effected.
- The use of liquids and solutions of relatively high specific gravity for the classification 20 of materials such as ores and the like in various forms of classifiers and jigs is known, and the use of mixtures of liquids and finely divided insoluble solid matter such as clay, mud, silicates of alumina, fire
- 25 clay and the like, which when mixed with liquid tend to remain suspended in it, is also known. Attempts have been made to effect improvement in classification by utilizing the greater losses in the weights of materials
- 30 immersed in liquids, solutions or mixtures of relatively high specific gravity, as compared with the losses in weights of such materials immersed in water or other liquid of less specific gravity.
- 35 Our invention relates to the use of fluid masses of relatively high specific gravity consisting of agitated mixtures of liquid and comminuted insoluble solid matter heavier than the liquid, in the classification of materials by means of the differences in the relative falling velocities, in such fluid masses, of materials of different specific gravities, sizes, shapes and cleavage. Our improvement consists in the production and
- 40 maintenance of such fluid masses by using as the principal solid constituent of such fluid masses comminuted insoluble matter heavier than the liquid, the individual particles of said matter being of such material,
- 45 size, shape and nature as to sink by gravity in the liquid used and that require continual agitation to maintain and to preserve the homogeneity of the fluid mass by keeping the particles of solid matter distributed
- 50 through the liquid to form a fluid mass of the desired specific gravity and of low viscosity, and in the classification of materials differing in their specific gravities, sizes, shapes, cleavage or other physical properties, by immersion in said fluid mass.
- In the classification of such materials by mixtures of relatively high specific gravity consisting of liquid and clayey materials, or the like, such as tend to remain in suspension in the liquid, the viscosity of such mix-
- tures tends to prevent or to retard classification, not only by the retardation in the falling velocities as already described, but by reason of the effect of eddy currents which are produced in viscous mixtures in the operation of all forms of apparatus in which such classification can be carried out. The detrimental effect of eddy currents is well understood in the classification of material in apparatus using water as the liquid medium to effect classification, and such apparatus is always designed to reduce, so far as is possible, the production of eddy currents and to control or to minimize their effect. The handling of a liquid or of a mixture of relatively high viscosity in any known type of apparatus used for the classification of materials cannot be effected without the production of eddy currents, and the suppression or control of eddy currents in a viscous liquid or viscous mixture presents greater difficulties than those to be overcome when the liquid or mixture has relatively high mobility or fluidity. The effect of eddy currents in preventing proper classification of the materials, by causing a remixing of materials sought to be separated, is also much greater with viscous liquids or viscous mixtures or suspensions than with those having high fluidity.
- In thus comparing the conditions attendant upon the use of mixtures of relatively high viscosity with fluid masses of relatively low viscosity, we do not intend to convey the impression that viscous mixtures cannot be used in classifying materials of different specific gravities, sizes and shapes, because the loss in weight of such materials by immersion may even in quite viscous mixtures or suspensions in some cases permit a useful classification of the materials to be made; but in most cases such classification can be made more easily, more quickly and with greater certainty, and each class of material separated will contain less material that properly belongs with other classes, when a fluid mass of high mobility and fluidity is used than when a mixture of a viscid type is used.
- We are aware that the difference in the falling velocities of materials immersed in suspensions or mixtures of mud, clayey, or other similar materials which tend to remain suspended in water and which do not quickly settle by gravity, has been used in separating materials of different specific gravities, and we do not herein claim the use of mixtures of liquid with very finely divided solids of such types. Such mixtures do not produce fluid masses of the type used in carrying out our invention, but produce a "mud" having relatively high viscosity in which the materials do not quickly or readily sink, whereas fluid masses of the type used in carrying out our invention have a

fluidity (or mobility) approximating that of the water or other liquid used in producing them. This specific difference in viscosity may perhaps be due in part to the fact that when solid matter is in an extremely finely subdivided condition, the individual particles have such small mass that they must lie very close to each other in such mixture, perhaps being separated by a mere film of water or other liquid used (or may have a film of liquid strongly adhering to each particle, constituting a liquid envelop that attracts and adheres to other like envelops), so that the attraction of 10 particle for particle tends to tie the mass together and thus produce a mixture of relatively high viscosity and low mobility, whereas if a mixture be produced consisting of particles that are of such size and weight 15 and character as to fall freely in water, or other liquid, and that require continuous agitation to keep them suspended in said liquid, then a fluid mass of relatively high specific gravity is produced having a viscosity which may be very little, if appreciably, greater than that of the liquid used. Whether this be the true explanation of the 20 difference in viscosity or not, or whether the cause may not be due to some other property of such materials, the fact remains that fluid masses of the described type are highly fluid, whereas mixtures of relatively high specific gravity consisting of liquid and materials that do not readily sink in the liquid 25 are more or less viscid. We find, for example, that with mixtures of water and ordinary quartz sand, such as may be found along the New Jersey coast, fluid masses of relatively high specific gravity can be produced, say 1.50 to 1.70, and of such perfect fluidity, that the hand when passed through water superimposed upon said fluid mass can enter the fluid mass below it without detecting the difference in the fluidity of the 30 said fluid mass and of the water superimposed upon it, and that the hand or any object immersed in such fluid mass can be withdrawn without having any considerable quantity of such fluid mass adhering to it, whereas this is not true of fluid masses of 35 relatively high specific gravity consisting of clay or other similar material mixed with water, unless the immersed object be greased or very highly polished. In utilizing the 40 differences in falling velocities of materials in such fluid masses for the separation of materials of different specific gravities, we are able to effect separations which cannot be effected, or that cannot be quickly effected, with mixtures consisting largely or principally of clay-like or other materials which tend to form mixtures of relatively high viscosity.

The differences in the relative weights of 45 materials when immersed in fluid masses of relatively high specific gravity are very much greater than the differences in the weights of these materials in water or in air. For an example, if the specific gravities of coal, bony coal and slate be respectively 1.30, 1.45 and 2.00, their weights in air, in water and in a fluid mass of 1.25 specific gravity, are in the ratios;

Relative weights.

	Coal.	Bony coal.	Slate.	75
In air, as-----	65	to 72 $\frac{1}{2}$	to 100	
In water, as-----	30	to 45	to 100	
In a fluid mass of 1.25 sp. gr., as-----	6 $\frac{1}{2}$	to 25 $\frac{1}{2}$	to 100	80

and as the falling velocities of materials, for particles of equal size and similar shape, depend upon their relative immersed weights, it is evident that the falling velocities of the lighter as compared with the heavier 85 materials immersed in said fluid mass relatively will be very much less than the falling velocities of these materials when immersed in water or other liquid of less specific gravity than said fluid mass, hence in 90 using a high gravity fluid mass to effect such separations, it is important that the fluid mass should be highly mobile or fluid and not sticky or viscid, because high viscosity will further and greatly retard, and 95 in many cases will prevent, the separation from being made, and in all cases will prevent the separation from being as completely effected as when a non-viscous fluid mass is used.

In a patent issued to Thomas M. Chance dated May 1, 1917, No. 1,224,138 for method and apparatus for washing coal and concentrating ores, the use of fluid masses of a type somewhat similar to those herein described is described and claimed for separating materials of different specific gravities by the flotation of the lighter constituents and the sinking of the heavier constituents, the fluid mass used having a specific gravity 105 high enough to effect flotation of the lighter constituents of the materials to be separated but low enough to permit the heavier constituents to sink. In that patent, separation or classification by differences in falling 110 velocities is not described or claimed, the separation by flotation being effected by differences in specific gravity irrespective of the size or shape of the materials to be separated. In an application filed August 27, 120 1917, Serial No. 188,431, Thomas M. Chance has described the use of a compound fluid mass comprising two or more zones of different specific gravities and has claimed the same for making separation of three or more 125 materials of different specific gravities, using fluid masses of a type somewhat similar to those herein described, but the separation as described and claimed therein is by flotation of the lighter and sinking of the heavier 130

materials irrespective of the size and shape of the materials and of the differences in falling velocities of the materials in such fluid masses.

5 In the operation of the present invention if materials of less specific gravity than that of the fluid mass be present in the materials to be classified, they will of course be removed by flotation as described in said Patent No. 1,224,138 above cited, and this may at times occur accidentally or incidentally in some of the types of apparatus used in the practice of our method, and by differences in the specific gravity of the fluid mass occurring in different parts of the apparatus, but we do not herein claim separation of any constituents of the materials to be classified by flotation due to the specific gravity of the fluid mass being sufficient to float such constituents, nor do we herein claim the separation by sinking of heavier constituents of such materials in such fluid mass because such constituents are of greater specific gravity than that of the fluid mass, and we have therefore limited our claims herein to method and apparatus whereby classification (or separation into classes of approximately equal falling velocities) is effected by the differential action of fluid masses of relatively high specific gravity in retarding the falling velocities of the materials to be separated, whereby it becomes possible to separate the materials into two, three or more classes in each of which the constituents thereof have approximately equal falling velocities in the fluid mass used, and in which such classification is effected by, and results from, differences in the falling velocities in such fluid mass of the materials to be classified.

For reasons already given we do not claim herein separation or classification by means of mixtures in which the comminuted solid constituent particles whereof tend, by reason of their character, size, shape, composition or other physical property, to remain suspended in the liquid constituent thereof, or which do not readily sink or settle by gravity in said liquid constituent, and we therefore have limited our claims herein to a method and apparatus whereby classification is effected by fluid masses of the described type which require continuous agitation to keep the solid particles thereof in suspension, and to the use, in effecting such classification, of solid matter of such nature as will, when agitated with liquid, produce fluid masses of high mobility and relatively low viscosity.

60 The drawings Figures I, II and III illustrate the application of the method to some types of classifying and concentrating appliances, but it will be understood that the application of the method is not confined to these particular types of appliances.

They are vertical cross-sections and elevations of three different types of apparatus embodying our invention.

Fig. I is a vertical cross-section and elevation showing the working parts of a coal jig of the movable pan type actuated by an eccentric, and in which the two products made, coal and "jig rock" (slate etc.), are discharged into scraper conveyors for removal from the jig tank, like many in common use in the anthracite coal fields of Pennsylvania.

The apparatus as shown consists of a tank or receptacle 1, adapted to contain a fluid mass of the described type and a fluid mass 2 contained therein and filling said tank 1 up to or approximating the position of the overflow outlet 3. The fluid mass numbered 2 is indicated by the broken horizontal lines used conventionally to represent liquid (water) and stippled to represent the solid constituent of said fluid mass. The bottom of the tank 1, consists of perforate plates 4, 5, 6, 7, below which are pressure chambers 8, 9, 10, 11 adapted to hold water under pressure, and each of which is provided with an inlet for water under pressure, shown as pipes, 12, 12, suitable for connection to any suitable source of supply of liquid under pressure, and a clean-out hole 13 with valve or cock shown as a plug, 14, for closing same. The movable pan 15 is actuated by the eccentric 16 through the eccentric rod 17, to which it is attached and guided in its movement by the pin 18. This pan 15 is provided with a perforate bottom with perforations 19 large enough to permit of the free flow of the fluid mass 2 through them, and with an adjustable feed-gate 20 controlling the coal feed chute 28 and an adjustable slate delivery gate 21.

The coal discharge chute 22 delivers the coal to one side of the center line of the pan 15, so that the coal will fall into and be removed by the coal scraper elevator 23, 110 and the slate discharges through the gate 21 on the opposite side of the center line of the pan 15 so that with the aid of the warped baffle plate 24 it will fall into and be removed by the slate scraper elevator 25. 115

In apparatus of this movable pan jig type the coal (ore or other material) and material to be separated therefrom is fed into the movable pan 15 from the feed chute 28, and fills the pan to the level of the top of the coal discharge chute 22. The mass of materials filling this pan is raised at each upward stroke thereof produced by revolutions of the eccentric 16, and falls under action of gravity during the downward stroke thereof, the downward stroke being made at a velocity exceeding the falling velocity of the materials in said fluid mass. The operation is similar to that which occurs when water is the fluid me- 130

dium in which the jiggling is carried out, but with this important difference that owing to the fact the fluid mass has higher specific gravity than that of water, the differences in the falling velocities of the materials under separation is greater than if water alone is used as a fluid medium, so that the faster falling particles of said materials fall more quickly as compared with the slower falling particles and the separation is thus more rapidly and fully effected than when the separation is produced by differences in falling velocities in water. The more rapidly falling material, comprising the reject, if coal is being washed, or concentrates, if ore is being concentrated, is delivered from the lower portion of pan 15, under gate 21 to elevator 25, warp baffle 24 assisting this delivery while the slower falling material, comprising the coal, if coal is being washed, or refuse if ore is being concentrated, discharges through chute 22 into elevator 23, said elevators 23 and 25 serving to remove the separated materials from the fluid mass. In the drawing Fig. I a shallow body of water is shown superimposed above the fluid mass. This body of water is practically the same in quantity as that which is supplied through the perforate bottom and sides to provide agitation of the fluid mass, the water so admitted rising through the fluid mass and flowing out of the apparatus through the overflow 3. It will of course be understood that while the drawings all show a body of liquid above the fluid mass, such supernatant liquid is not an essential part of our invention and has not been claimed herein.

Fig. II is a vertical cross-section and elevation showing the working parts of a coal jig of the fixed pan, water pulsation type, in which the two products made, coal and "jig-rock" (slate etc.), are discharged from the pan into or within the reach of scraper conveyers for removal from the apparatus, like many in common use in the anthracite coalfields of Pennsylvania. The apparatus as shown consists of a tank or receptacle 1, adapted to contain a fluid mass 2 of the described type, and a fluid mass 50 contained therein filling said tank 1 up to, or approximating to, the position of the overflow outlet 3. The fluid mass numbered 2 is indicated by the broken horizontal lines 55 used conventionally to represent liquid (water) and stippled to represent the solid constituent of said fluid mass. The bottom of the tank 1 consists of a perforate plate 4 below which is a pressure chamber 8, 60 adapted to hold water under pressure, and is provided with an inlet or inlets for water, shown as a pipe 12 suitable for connection to any suitable source of supply of liquid under pressure and a clean-out hole 13 with

valve or cock, shown as a plug, 14, for closing same.

The fixed pan or compartment 26 is provided with a perforate bottom with perforations 19' large enough to permit the fluid mass 2 to flow through them and with an adjustable slate delivery gate 21. The coal rides over the coal discharge lip 27' and is removed by the coal scraper elevator 23 and the slate discharges through the gate 21 to the slate scraper elevator 25. The feed from the coal feed chute 28 is controlled, distributed and directed by the adjustable feed gate 20'. The fluid mass 2 is caused to pulsate or to oscillate through the perforations 19' by the reciprocating motion of the plunger or piston 29 actuated through the connecting rod 17' by the eccentric 16'. The tank is provided with perforate baffle plates 30 to control the directional flow of the fluid mass, the perforations in said baffle plates being large enough to permit flow of the fluid mass 2 through them.

In apparatus of this fixed pan jig type the operation is similar to that of the movable pan type above described, the materials to be separated in this case being raised by each upward pulsation of the fluid mass through the perforate bottom of the fixed pan and falling in said fluid mass during the downward pulsation of the fluid mass, the separation being by difference in falling velocities between the particles of materials to be separated, these differences being greater in the fluid mass than in water, the separating action occurring in part during both the upward and downward pulsations of the fluid mass, the difference in falling velocities causing the slow falling particles to be lifted more rapidly as compared with the faster falling particles during the upward pulsations, than if water is used as the fluid medium in which to jig the materials, thus making more rapid and efficient separation of the materials. The more rapidly falling material comprising the reject, if coal is being washed, or concentrate, if ore is being concentrated, falls to the perforate bottom of the fixed pan 26 and is translated laterally across said bottom by the pulsations of the fluid mass, this movement being induced by reason of the inclination of said perforate bottom. Said faster falling materials pass under gate 21 and into elevator 25 while the slower falling material rides across said pan 26 and passes over discharge lip 27 into elevator 23, said elevators 23 and 25 serving to remove the separated materials from the fluid mass. In the drawing Fig. II the fluid mass has shown superimposed upon it a thin body of water the height of which is limited by the overflow 3. In the casing to elevator 25, a higher body of water is

shown above the fluid mass in the bottom of the elevator casing. This condition arises from the fact that the elevator casing not being supplied with agitating means, the 5 sand of the fluid mass drops to the lower part of the casing, leaving clear water, or water with very little sand, in the upper portion and the hydrostatic pressure of the greater height of fluid mass in the jig tank 10 1, maintains the surface of water in the elevator boot 25 at a greater height than the overflow 3.

Fig. III is a vertical cross-section and elevation showing the application of the 15 method in using appliances similar to those used in surface current classifiers and trough washers, in which 40 is a trough or tank the bottom of which consists of a number of hoppers or pockets 41, 41^a, 41^b, 41^c, with per- 20 forate sides or inclined bottoms 42 below which are pressure chambers 43 supplied with liquid under pressure from the pipes 44 through a conduit 45 in communication through a control valve 46, with a pump 47 25 driven by power from any suitable source. The perforate bottoms 42 are for the supply of hydraulic liquid (water) for the agitation of the fluid mass contained in said pockets (41, 41^a, 41^b and 41^c). This liquid, together 30 with that introduced by small pipes 60 at or below the base of said pockets, permit the maintenance of uniform fluidic properties throughout said pockets, the liquid introduced by small pipes 60 supplying agitation 35 over that area of the pockets not covered by perforate bottoms 42 and thus preventing the formation of solid banks in the lower portions of said pockets that would hinder the fall of the separated materials prior to 40 withdrawal from the apparatus. A further function of the liquid introduced to maintain agitation in the pockets 41, 41^a, 41^b and 41^c is to assist the agitation of the body of fluid mass flowing through trough 40. The 45 tank or trough 40 is provided with outlet 48, for fluid mass passing over the adjustable overflow gate 49, connected with a pump 50 and conduit 51 and with a discharge 52 at the upper end of the trough or tank 40, the 50 operation of which continuously pumps fluid mass into the upper end of said trough or tank 40 and continuously removes fluid mass from the lower end of said trough, thus establishing a flow of fluid mass through the 55 tank or trough 40. A feeder, shown as a feed chute 53 and apron 54 provides a means of feeding material to be separated into said moving fluid mass, those parts that settle in it most quickly descending into the first 60 hopper or pocket 41^c, and those that have the slowest falling velocity fall into the last pocket 41. To facilitate said fall one or 65 more of the pockets may be supplied with increased agitation, and thus hold a fluid mass of lower specific gravity, by making

the perforations in the sides or bottom of said hopper larger or more numerous than those in the sides or bottom of the preceding pocket. Each of these pockets 41, etc., is provided with means for drawing off or 70 removing the separated product, this being shown as a trap consisting of two gates or valves operated by thrust cylinders or by link and lever 59 operated by hand or any suitable source of power. The material before being trapped out of the pockets 41 is washed more or less free from the fluid mass by liquid (water) flowing from the pipes 44 through the small pipes 60 which discharge into or below the base of the pockets 41. 75 The material thus trapped out is discharged on dewatering screens 61, the water and fluid mass passing through these screens into the trough 62, which is provided with hoppers 63 to catch the sand, which flows through 80 the conduits 64 to the inlet of a pump 65, through which it is returned by the conduit 66 to the trough or tank 40, the water thus trapped into the tank 62, together with over- 85 flow water from tank 41, flowing through the pipe 67 to tank 62 flows into the suction of the pump 47. The tank 62 is provided with liquid (water) supply through 68 by means of "constant level valve and float" 69 and 70. An overflow wier 71 is provided to keep 90 the top of liquid (water line) in tank 40 at any desired level.

In apparatus of this trough type, the materials to be separated are fed into the fluid mass flowing through the trough 40 and are 100 thus translated longitudinally while they are falling in the fluid mass, those particles of higher falling velocity reaching the bottom of the trough or the pockets 41, 41^a, in the bottom after traveling a less distance than 105 the particles of slower falling velocity, the operation being similar to that which takes place in trough and "surface current" classifiers in which classification is effected 110 through differences in falling velocities in water of the material to be classified, with this important distinction, that in our invention the differences in falling velocities of the materials to be separated is greater than their differences in falling velocities in 115 water, thus effecting a more rapid and efficient separation. In the drawing Fig. III the fluid mass occupying the tank 40 and pockets 41, 41^a, 41^b and 41^c, is diagrammatically indicated by nearly horizontal broken lines representing liquid (water) and stippling to represent the solid component (sand) of said fluid mass, and liquid (water) superimposed thereon is diagrammatically represented as occupying the space between the lines A—A and B—B by nearly horizontal broken lines.

It will be observed that in the operation of the method in all of these types of appliances, and this applies to any type of ap- 120 125 130

pliance in which the method may be carried out, that the material to be classified, or separated into different classes, must be completely immersed in the fluid mass so 5 that the different materials may separate in different zones or in different parts of the apparatus by reason of the time element introduced by the differences in falling velocities.

10 It will also be noted that this method provides a means for the separation by classification of products which may be termed "middlings," that is, products which have less falling velocity than the most rapid 15 falling particles and greater falling velocity than those having the least rate of fall, and that this provides a method for the separation of low grade ores which require re-crushing and further treatment, or for the 20 separation of laminated coal, *i. e.*, coal and slate or bony coal adhering to it, or with admixture of pyrite, which requires re-crushing for further treatment, or for the separation 25 of an intermediate product in coal washing, which may consist of low grade coal and bony coal which has value as fuel but is not equal to the best coal.

It will be understood that in employing 30 jigs of the plunger type apparatus in effecting classification, that the "suction stroke" should be suppressed if it be desired to prevent the fine and heavy particles from being thrown down into the hutch, and that this can be done by the use of "hydraulic water," 35 valved plungers or other means in use in the operation of jigs for suppressing the effect of the suction stroke.

It will be understood that the perforations in the plates shown on the drawing are 40 not made to scale, but that the holes may be of such diameter and such spacing from center to center as will pass sufficient liquid under the head used to effect the desired agitation. It will be understood further 45 that perforated plates as shown by the apparatus are intended diagrammatically to indicate the location of such plates, and that plates of other types of construction than those shown may be used, such as those with 50 wearing plates or strips to protect the plates from attrition caused by scraper flights, conveyers and material dragged over them, such as have been used for the protection of perforated plates from wear, and that for 55 the purpose of such protection a heavy perforated plate may be superimposed upon a smaller or lighter plate.

Before proceeding to carry out our 60 method of classification by means of fluid masses of the described type, by applying it to the classification of any given material, the material should be prepared by removing, by screening, or other means, those particles that are too small for classification 65 by the fluid mass that is to be used.

If to a fluid mass of the described type there be added (through the introduction of materials to be classified) particles approximating in size to that of the particles of the solid constituent of the fluid mass, such added particles if appreciably heavier than those composing the fluid mass, will (unless the fluid mass be violently agitated) tend to sink to the lower part of the fluid mass and there form a fluid mass of correspondingly 70 higher specific gravity, or, will remain suspended as a constituent part of the fluid mass, correspondingly increasing its specific gravity, or, if lighter than the solid constituents of said fluid mass will tend to remain as 80 a constituent part of said fluid mass, correspondingly decreasing its specific gravity, or will rise above the fluid mass and there remain, superimposed as a fluid mass of less specific gravity upon the fluid mass used. 85 The disposition in the fluid mass of particles approximating in size to those of the fluid mass will depend largely upon the character of the agitation by which the fluid mass is maintained at the desired specific 90 gravity, and will also depend largely upon the specific gravity of such particles and to some extent upon their shape and possibly upon other physical properties.

In studying the properties of fluid masses 95 of the described type, it should be remembered that while such fluid masses exhibit most of the physical properties of true liquids of high specific gravity, in that they produce the same hydrostatic pressures as 100 liquids of the same specific gravities, cause bodies immersed in them to lose the same weight as if immersed in a liquid of equal specific gravity, "seek their own level" like true liquids, flow over a weir like a true liquid, etc., yet they do not act precisely like liquids of high specific gravity upon bodies immersed in them which approximate in size to (or are smaller than) the particles of 105 their solid constituents, immersed bodies of such size being acted upon by the agitation supplied to keep the solid constituents of the fluid mass in suspension and therefore tend to become a constituent of the fluid mass. 110 The introduction of particles approximating in size to those of the fluid mass merely constitutes an addition to the fluid mass unless the particles added are much heavier or much lighter than those of which the fluid mass is composed. The materials to be 115 classified by the use of this method should therefore be appreciably larger, or much heavier, than the particles composing the fluid mass, in other words, they must be capable of sinking in such fluid mass and 120 of developing marked differences in their falling velocities in said fluid mass.

The drawings show the admission of 125 liquid constituent of the fluid mass to effect or to maintain or to assist in maintaining 130

agitation in the form of jets from a source of liquid supply under pressure, these jets being vertical or at any desired angle, the jets issuing from the orifices of pipes, tubes or nozzles of any desired form, shape, or length, the small perforations in the perforated plates being intended to represent diagrammatically such tubes, pipes or orifices, and are in fact tubes of short length connected to a source of supply of liquid under pressure. It will be further understood that the quantity of liquid so admitted and used may vary from none up to any desired quantity, depending upon the degree of agitation produced by other means provided to maintain the fluid mass of the required consistency.

It will be understood that in carrying out our invention we do not limit ourselves to the use of the particular appliances shown by the drawings nor to the details of these appliances, nor to the particular means shown to effect agitation, to feed the materials into the apparatus or for removing the materials after separation is effected, as these must be adapted to the character of materials to be separated; thus, the removal by trapping out the materials, as shown by Fig. III, is best adapted to be used when the materials are relatively fine, removal by elevators, indicated diagrammatically by the scraper conveyers shown by Figs. I and II being better adapted to the purpose when the materials to be separated are relatively coarse.

In using the type of fluid mass herein described as a medium to effect classification, the fluid mass may be agitated by any known means for effecting agitation of fluid masses, either by circulation of the fluid mass, by mechanical appliances or by fluid introduced under pressure, that is, with sufficient velocity to effect agitation. The drawings illustrate means for effecting agitation by all of these methods, the centrifugal pump, the plunger, the movable pan and the pressure chambers with jets issuing through the perforate plates being intended diagrammatically to show agitation by circulation, by mechanical and by hydraulic means.

When liquid (water) is the sole means used for agitating the fluid mass, the velocity of the upward current of liquid in the apparatus as a whole must be less than the falling velocity in the liquid of the smallest solid particles of the fluid mass, unless it be desired to carry the fluid mass out of the apparatus.

Our invention is also useful in combination with the use of the method of said Patent No. 1,224,138 and constitutes an improvement by which a "middlings" product can be separated, that is, a product heavier

than the lightest and lighter than the heaviest of the materials which are to be washed or concentrated, or for definitely controlling the disposition of such "middlings" product by causing it to remain with either the lighter or the heavier product as may be desired, or for splitting it into two products of different specific gravities and different falling velocities. In the operation of the method described in the above mentioned Patent No. 1, 224,138, as applied to coal washing, if the fluid mass used be of high enough specific gravity to float both pure coal and coal of rather high ash, then some bony (very high-ash) coal approximating in specific gravity to that of the fluid mass, may not readily sink, but by slight eddy currents in the fluid mass, or by being held up by the buoyancy of lighter pieces of coal, may remain with the coal and be discharged with it; if the specific gravity of the fluid mass be reduced to permit this bony coal to sink readily, then some of the "rather high-ash" coal is likely to be carried down by eddy currents or by becoming enmeshed with the slate, fireclay and bony coal, so that the "reject" may consist of a mixture of slate, fireclay, bony coal and "rather high-ash" coal. Similarly, in the concentration of ores by the method of said Patent No. 1,224,138, in which the gangue, or waste, is to be floated by the fluid mass and the ore permitted to sink through the fluid mass, particles of low-grade ore (middlings) consisting of pieces of gangue containing (or attached to) some of the heavier (valuable) mineral constituent of the ore, may, as the specific gravity of the fluid mass be made relatively high or low, tend either to float with the gangue or to sink with the high-grade ore.

The separation of such "middlings" products can be effected by the use of compound fluid masses having zones of different specific gravities adapted to effect such separation, for which method Thomas M. Chance has filed an application for patent dated August 27, 1917, for method of washing coal and concentrating ores, Serial No. 188,431, and we do not herein claim the use of compound fluid masses, although the operation of the method described in this application may at times incidentally or accidentally create zones of different specific gravities in the fluid mass employed in the operation of our new method as herein described, but such zones are not used to effect separation by flotation. When the fluid mass used is of less specific gravity than that of the materials desired to be thus separated, separation into classes cannot be effected by a purely gravimetric or flotation method, as described in said Patent No. 1,224,138, but can be effected by utilizing the differ-

ences in the falling velocities of said materials in said fluid mass, as described in the operation of our present invention.

The effect of viscosity in a fluid mass is

- 5 to make a greater relative reduction in the falling velocity of materials of relatively low specific gravity and in the falling velocity of particles of material of higher specific gravity but of relatively small size, than in
- 10 the falling velocity of materials of relatively higher specific gravity and in the falling velocity of particles of relatively larger size respectively, and this reduction in the falling velocity of particles of relatively
- 15 small size and in materials of relatively low specific gravity tends to prevent them from sinking and causes them to be buoyed up readily by relatively slight eddy currents in said fluid mass and to prevent their separation
- 20 from materials of less specific gravity and from smaller particles of material; while it increases the time required for the separation of all classes of materials, renders the separation "sluggish," reduces the
- 25 possibility of making a clean separation and greatly increases the difficulty of separating solid matter of the fluid mass adhering to the separated products from such products.

In practising the method of separation by

- 30 flotation, U. S. Patent No. 1,224,138 above referred to, moderate viscosity of the fluid mass may not retard or prevent satisfactory separation of material lighter than the fluid mass from material heavier than the fluid
- 35 mass, (except possibly as to the separation of very small particles of the heavier material), but when for the purpose of separation certain materials must be permitted to sink so as to fall farther than other materials
- 40 from which they are to be separated and certain other materials must be permitted to sink and fall farther than either, with perhaps still others that must fall still farther in a given time, such separation can
- 45 be effected more quickly and efficiently by using a fluid mass of low viscosity than one of high viscosity.

Our invention is based upon our discovery of the remarkable fluidity or mobility of fluid masses that may be produced by the means herein described, upon our discovery of the very low viscosity of such fluid masses, upon the peculiar advantages that may be attained by employing such fluid masses as a medium (substitute for water or other liquid) in which to effect classification through differences in the falling velocities in such fluid masses of the materials to be separated by classification and upon the advantages such fluid masses possess over fluid masses of a more or less viscous type. These discoveries were made by us in experimenting with different forms of apparatus for carrying out the two inventions of Thomas M. Chance relating to flotation by fluid

masses above referred to, and one other invention of his for which he filed application for patent on August 27, 1917, Serial No. 188,430.

The term "fluid mass" as used in this specification and the claims hereof, is intended to designate an agitated mixture of relatively low viscosity consisting of liquid and comminuted solid matter heavier than the liquid and insoluble therein, such solid matter consisting principally of appreciably coarse granular material of such kind, size, shape and nature as to sink readily by gravity in said liquid and that requires continuous agitation to keep it suspended in the liquid and to maintain the fluidic properties, relatively high specific gravity and relatively low viscosity of such fluid mass; the term "middlings" is intended to mean and to include constituents of the materials to be separated that are heavier than the lighter constituents and lighter than the heavier constituents of said materials, in ores consisting principally of low-grade ore and in coal of high-ash or bony (very high-ash) coal; the term "ore" or "ores" is intended to include materials containing non-metallic elements or substances (e. g. graphite, etc.) and also to include metallic products, (e. g. metallic filings mixed with other material)

95 materials and substances such as ordinarily would not be called ores but which have properties or qualities that permit of their separation by the method herein described; the term "water" is intended to mean any 100 liquid suitable for making a fluid mass of the described type, and the term "sand" is intended to mean any appreciably coarse granular insoluble material heavier than the liquid used and suitable for making a fluid 105 mass of the described type. It will of course be understood that the specific gravity of the fluid mass used in carrying out our invention must be less than the specific gravity of the materials which are to be 110 separated, separation being effected by differences in falling velocities of such materials and it is evident that unless the specific gravity of the fluid mass is less than the specific gravity of these materials, they 115 would not fall through it but would float upon it. The fluid mass used in carrying out our invention must, moreover, be of greater specific gravity than the liquid component of said mass in order that it function to 120 check the falls of the materials to be separated at ratios differing from the falling ratios of said materials in that liquid alone.

Having thus described our invention, we claim,

1. The method of separating materials of unlike physical characteristics which consists in submerging said materials in a continuously agitated fluid mass composed of a mixture of liquid and comminuted granular

solids, said materials being of greater and said liquid of less specific gravity than said fluid mass and said solids being of such nature as to remain suspended in a hydraulic current that will not support the materials to be separated by differences in falling velocity; in causing said materials to fall in said fluid mass, whereby the materials of relatively high falling velocity position themselves below those of relatively low falling velocity, the differences in falling velocities of said materials being greater in said fluid mass than in said liquid alone; and in separately removing said materials so positioned from said fluid mass.

2. The method of separating materials of unlike physical characteristics which consists in submerging said materials in a continuously agitated fluid mass composed of a mixture of liquid and comminuted granular solids, said materials being of greater and said liquid of less specific gravity than said fluid mass and said solids being of such nature as to remain suspended in a hydraulic current that will not support the materials to be separated by differences in falling velocities; in causing said materials to fall in said fluid mass, whereby the materials of relatively high falling velocity position themselves below those of relatively low falling velocity, the differences in falling velocities of said materials being greater in said fluid mass than in said liquid alone; in separately removing said materials so positioned from said fluid mass; in separating from said materials so removed portions of said fluid mass admixed therewith; and in returning to said fluid mass portions of said mass thus separated from said removed materials.

3. The method of separating materials of unlike physical characteristics which consists in submerging said materials in a continuously agitated fluid mass composed of a mixture of liquid and comminuted granular solids, said materials being of greater and said liquid of less specific gravity than said fluid mass and said solids being of such nature as to remain suspended in a hydraulic current that will not support the materials to be separated by differences in falling velocities; in causing said materials to fall in an upwardly rising current of said fluid mass whereby the materials of high falling velocity position themselves below those of low falling velocity, the differences in falling velocities of said materials in said fluid mass being greater than in said liquid alone; and in separately removing said materials so positioned from said fluid mass.

4. The method of separating materials of unlike physical characteristics which consists in submerging said materials in a continuously agitated fluid mass composed of a mixture of liquid and comminuted granular

solids, said materials being of greater and said liquid of less specific gravity than said fluid mass and said solids being of such nature as to remain suspended in a hydraulic current that will not support the materials to be separated by differences in falling velocities; in causing said materials to fall in a moving current of said fluid mass, said fall and said motion coacting to position the materials of high falling velocity in a zone relatively remote from that occupied by the material of relatively low falling velocity, the difference in falling velocities of said materials in said fluid mass being greater than in said liquid alone and in separately removing said materials so positioned from said fluid mass.

5. The method of separating materials of unlike physical characteristics which consists in submerging said materials in a continuously agitated fluid mass composed of a mixture of liquid and comminuted granular solids, said materials being of greater and said liquid of less specific gravity than said fluid mass and said solids being of such nature as to remain suspended in a hydraulic current that will not support the materials to be separated by differences in falling velocities; in causing said materials to fall in a moving current of said fluid mass, said fall and said motion coacting to position the material of high falling velocity in a zone relatively remote from that occupied by the material of relatively low falling velocity, the differences in falling velocities of said materials being greater in said fluid mass than in said liquid alone; in separately removing said materials from said fluid mass and in returning to said fluid mass portions of said mass admixed with said materials.

6. Apparatus for the separation of materials of unlike physical characteristics comprising in combination a receptacle adapted to contain a fluid mass; a continuously agitated fluid mass contained therein composed of a mixture of liquid and comminuted solids, said materials being of greater and said liquid of less specific gravity than said fluid mass and said solids being of such nature as to remain suspended in a hydraulic current that will not support the materials to be separated by differences in falling velocities; means for submerging said materials in said fluid mass; means for separately removing said materials from said mass after they are positioned in different zones by reason of their different rates of fall in said mass; and means for agitating said fluid mass.

7. Apparatus for the separation of materials of unlike physical characteristics comprising in combination a receptacle adapted to contain a fluid mass; a continuously agitated fluid mass contained therein composed of a mixture of liquid and commi- 130

nuted solids, said materials being of greater and said liquid of less specific gravity than said fluid mass and said solids being of such nature as to remain suspended in a hydraulic current that will not support the materials to be separated by differences in falling velocities; means for submerging said materials in said fluid mass; means for separately removing said materials from said mass after they are positioned in different zones by reason of their different rates of fall in said mass; means for agitating said fluid mass and means for reclaiming and returning to said fluid mass portions thereof added mixed with the separated materials removed therefrom.

8. Apparatus for the separation of materials of unlike physical characteristics comprising in combination a receptacle adapted to contain a fluid mass; a continuously agitated fluid mass contained therein composed of a mixture of liquid and comminuted solids, said materials being of greater and said liquid of less specific gravity than said fluid mass and said solids being of such nature as to remain suspended in a hydraulic current that will not support the materials to be separated by differences in falling velocities; means for submerging said materials in said fluid mass; means for separately removing said materials from said mass after they are positioned in different zones by reason of their different rates of fall in said mass; means for agitating said fluid mass; and means for causing movement of said fluid mass in said receptacle.

9. A method for separating and classifying materials comprising coal, impure coal, bone, slate, and other impurities, which consists in submerging said materials in a continuously agitated fluid mass comprised of a mixture of water and comminuted granular solids, said solids being of such nature as

to remain suspended in a hydraulic current that will not support the materials to be separated by differences in falling velocities, and said fluid mass having a specific gravity less than that of the said materials; in causing the materials to fall in said fluid mass, whereby the materials of relatively high falling velocity position themselves below the materials of relatively low falling velocity; and in separately removing said materials so positioned from said fluid mass.

10. A method for separating and classifying materials comprising coal, impure coal, bone, slate, and other impurities, which consists in submerging said materials in a continuously agitated fluid mass composed of a mixture of water and sand, said sand being of such nature as to remain suspended in a hydraulic current that will not support the materials to be separated by differences in falling velocities, and said fluid mass having a specific gravity less than that of the said materials; in causing the materials to fall in said fluid mass, whereby the materials of relatively high falling velocity position themselves below the materials of relatively low falling velocity; and in separately removing said materials so positioned from said fluid mass.

In testimony whereof, we have set our hands and seals, HENRY M. CHANCE at Philadelphia, Pennsylvania, on the first day of July, 1918, and THOMAS M. CHANCE at Baltimore, Maryland, on the fifth day of July, 1918.

HENRY M. CHANCE. [L. S.]
THOMAS M. CHANCE. [L. S.]
